UNITED STATES PATENT OFFICE

114,375

DESIGN FOR A BASKETBALL GOAL

Fred W. Fieldhouse, Louisville, Ky.

Application June 9, 1938, Serial No. 77,691

Term of patent 14 years

To all whom it may concern:

Be it known that I, Fred W. Fieldhouse, a citizen of the United States, residing at Louisville, in the county of Jefferson and State of Kentucky, have invented a new, original, and ornamental Design for a Basketball Goal, of which the following is a specification, reference being had to the accompanying drawing, forming part thereof.

The figure is a perspective view of a basketball goal embodying the new design.

I claim:

The ornamental design for a basketball goal, substantially as shown.

FRED W. FIELDHOUSE.
